UNITED STATES PATENT OFFICE.

JOHN LANGE, JR., OF MOBERLY, MISSOURI.

RAILWAY-CAR DRAFT-GEAR.

No. 835,540.

Specification of Letters Patent.

Patented Nov. 13, 1906.

Application filed October 31, 1904. Serial No. 230,794.

To all whom it may concern:

Be it known that I, JOHN LANGE, Jr., a citizen of the United States, residing at Moberly, in the county of Randolph and State of Missouri, have invented a new and useful Railway-Car Draft-Gear, of which the following is a specification.

This invention relates to the draft-gear of railway-cars, and has for its principal object to provide a novel form of gear that may be readily applied to cars of different construction.

A further object of the invention is to provide a draft-gear that may be used in connection with draft-springs of any desired size without structural change, the area of the spring-receiving pockets being altered in accordance with the size of the springs to be used.

20 A still further object of the invention is to provide a novel form of draft-gear that may be applied to a car whether loaded or unloaded, it being unnecessary to enter the car, and none of its securing devices extending 25 through the floor of said car.

A still further object of the invention is to provide a novel form of draft-gear in which the height of the coupler may be adjusted in accordance with the construction of the car.

30 With these and other objects in view, as will more fully hereinafter appear, the invention consists in certain novel features of construction and arrangement of parts, herein-after fully described, illustrated in the 35 accompanying drawings, and particularly pointed out in the appended claims, it being understood that various changes in the form, proportions, size, and minor details of the structure may be made without departing 40 from the spirit or sacrificing any of the advantages of the invention.

In the accompanying drawings, Figure 1 is a side elevation of a draft-gear constructed in accordance with the invention. Fig. 2 is a plan view of the same. Fig. 3 is a longitudinal sectional elevation of the draft-gear on the line 3-3 of Fig. 2. Fig. 4 is an inverted plan view of the draft-gear, the draw-bar, yoke, and spring being shown in section. 45 Fig. 5 is a transverse sectional elevation of the draft-gear on the line 5-5 of Fig. 3. Figs. 6, 7, and 8 are detail perspective views of portions of the device detached. Fig. 9 is a detail perspective view of one of the main sections of the draft-gear. Fig. 10 is a detail perspective view of the carry-iron detached. 50

Figs. 11, 12, and 13 are sectional plan views illustrating different adjustments of the spring-pockets for the reception of springs of different size. Fig. 14 is a detail sectional view of the rear portion of the draft-gear, showing particularly the adjustable blocks used in connection with the transom or body bolsters. Fig. 15 is a detail perspective view of one of the adjustable blocks detached. 65

Similar numerals of reference are employed to indicate corresponding parts throughout the several figures of the drawings.

The principal members of the draft-gear 70 are two web-plates 10 and 11, that are extended up between the two longitudinal sills 12 and 13 of the car, these plates being separated from each other in order to permit of the convenient introduction of the draft-gear 75 between sills that are spaced at different distances from each other, the sills of some cars being about eight inches distant from each other, while in other cars the space may be only six or seven inches. The vertically-extending webs of the two plates are secured to the respective sills, bolts 14, 15, and 16 being employed to hold the plate 11 to the sill 13, while bolts 17, 18, and 19 are employed to secure the plate 10 to the sill 12, and at the 80 points where the bolt-openings are formed each of the plates is provided with bosses that extend into suitable circular recesses in the inner faces of the sills in order that the connection may be rendered more secure. 90

The web-plates are provided with offsets 20 and 21, forming shoulders which engage against the bottoms of the sills and extend also into engagement with the bottoms of the end sill 22 and the buffer-block 23, and each of the plates is further provided with three upwardly-projecting lugs 24, 25, and 26, the lug 24 extending into a recess at the rear of the buffer-block, while the lug 25 extends into a recess at the front end of the longitudinal sills 100 and engages against the rear face of the end sill 22. The lug 26 of each of the plates is received within a suitable recess formed in the bottom of the longitudinal sill at a point between the end sill and the transom or body bolsters 33, these forming a secure connection for resisting the endwise thrust and relieving the bolts to a considerable extent. 105

Each of the plates is extended rearwardly over the transom 33 and is provided with a pair of spaced ears or lugs. The ears or lugs 27 and 28 of the side frame or plate 11 and

the ears or lugs 29 and 30 of the side frame 10 are spaced for a distance greater than the width of any transom or body bolster in ordinary use, so that when applied to any car 5 the frames or plates may fit in position. Between the sides of the transom and the adjacent ears or lugs are arranged filling-blocks 31 and 32, these being interchangeable and being fitted in place in accordance with the 10 position which the transom occupies with relation to the ears or lugs, and this being dependent to some extent on the width of the transom and its distance from the end sill of the car. Each of the blocks is preferably of 15 the construction shown in Figs. 14 and 15—that is to say, with three dimensions—and each block may be placed in the position shown in Fig. 14, or it may be turned to reverse the position of the top and bottom, or 20 it may be turned to occupy a position at a right angle to that shown to accommodate the position and the width of the transom. The blocks are held in position by locking-bolts 34 and 35, and each of the filling-blocks 25 is provided with two bolt-receiving openings, one being disposed at a right angle to the other, as shown in Fig. 15. This permits of the ready changing of the position of the blocks in accordance with circumstances. 30 Extending inwardly from each of the side frames or plates are spaced vertical ribs or webs 40 and 41, these being turned at the top at a right angle to form horizontal ribs 42 43 and 44 45, and said ribs form seats for the 35 reception of transversely-disposed bracing-plates 46 and 47. The rear plate 46 is provided at its lower end with an opening for the passage of a securing-bolt 37, that extends through openings in both of the main frames, 40 while the upper end of said plate 46 is held from movement in one direction by the ribs 40 and 41 and in the opposite direction by the heads of the securing-bolts 14 and 17. The front plate 47 is secured in place by bolts 45 48 and 49, extending through openings in the end sill, and as the opposite ends of said plate 47 bear against the vertical ribs 41 the main frame will be firmly locked to the end sill, and thus further relieve strain on the bolts. 50 In the inner faces of the two arms are formed pockets 50 51, in which fit transversely-disposed follower-plates 52 and 53, that are embraced by the yoke 54 of the draw-bar 55. The forward ends of the arms or plates are 55 provided with perforated ears or lugs 56 57, between which is arranged a carry-iron 58, that is held in position by transversely-disposed bolts 59 and 60. It will be noted on 60 reference to Figs. 3 and 10 that the bolt-receiving openings of the carry-iron are not arranged midway of the height of the iron, and this will permit the lowering of the height of the draw-bar if the position of the carry-iron 65 be reversed. In the position shown in Fig. 3

the draw-bar is supported in the highest position, and if the bolts are removed and the iron reversed to the opposite position the height of the draw-bar from the ground will be decreased, thus permitting proper adjustment of the draw-bars on cars of different size. 70

From the opposite end walls of the spring-pockets depend perforated ears or lugs 61 62 and 63 64, and between each set of lugs extends a lug-strap 65, forming the bottom of the spring-pocket, said lug-strap being held in place by bolts 67 68, having their heads disposed in countersunk recesses in the lug in order not to interfere with the draw-bar or its yoke. It will be noted that the bolt-receiving openings of the lug-strap are not arranged at a point midway of the vertical height of the lug-strap. In the position shown in Fig. 3 the lug-strap is in the highest 80 position, and the vertical height of the spring-receiving pocket is decreased; but if the bolts be removed and the positions of the lug-strap reversed the position of the rear end of the draw-bar will be lowered to correspond to the 85 adjustment of the carry-iron at the end of the car. 90

The construction, moreover, is such that if a draw-bar is to be removed it is merely necessary to remove one of the securing-bolts and 95 allow the lug-strap to swing down to a vertical position.

The area of the spring-receiving pockets may be altered in accordance with the size of the springs to be used, the greatest area of 100 the pocket being sufficient to permit the employment of two eight-inch springs placed side by side and extending between the following-plates.

In order to reduce the width of the pocket 105 where only a single eight-inch spring 73 is to be used, a filling-block 70 is placed in each of the pockets. These blocks, which are interchangeable, extend for the full length of the pockets, and each is provided with a pair of 110 extended lugs 75, that pass through suitable openings formed in the side frames, and said lugs are provided with openings for the passage of locking-keys 76, by which they are held in place. This adjustment is shown 115 clearly in Fig. 11, where a single eight-inch spring is used.

If it be desired to employ two six-inch springs placed side by side, the blocks 70 are removed and smaller filling-blocks 78 are 120 employed, these being provided with lugs 79 which may be passed through the openings in the side frames and locked in place by keys 80. This adjustment is shown in Fig. 13. If it be desired to employ one six-inch spring, the 125 filling-blocks 70 are placed in position and auxiliary blocks 81 are then inserted, as shown in Fig. 12, so that both the length and the width of the pockets are reduced.

The side frame-plates are preferably of a 130

reinforced formation, which may be advantageously effected by constructing the same on their outer sides with suitably-arranged strengthening ribs or webs, (designated generally by the reference characters 71 and 72 in certain figures of the drawings.)

It will be seen that the structure is such that the blocks may be removed or interchanged, so as to provide for the employment of springs of a strength and number proportioned to the character of the car without rendering it necessary to employ specially-made side frames or plates for each separate-sized spring.

15 It will be noted that all of the bolts in the improved device are horizontally disposed and are accessible from beneath the car-body, so that no necessity exists for entering the car to place or displace the device. This is a very important advantage, especially when repairing or renewing broken parts, as it frequently happens that the draft-gear is to be repaired or renewed upon loaded cars, and my improved device may be placed upon or 25 removed from the car without reference to the fact of its being loaded or empty, as above stated.

Having thus described the invention, what is claimed is—

30 1. In a draft-gear, the frame members having spring-receiving pockets, and interchangeable devices adapted to be removably mounted within said pockets and comprising means for varying the space occupied by the 35 spring according to the size of the latter.

2. In draft-gear, a frame having spring-receiving pockets, and means for varying the width of the pockets.

3. In a draft-gear, the frame members 40 having spring-receiving pockets, and interchangeable devices adapted to be removably arranged within said pockets for varying the length of the space therein according to the length of the spring to be employed.

45 4. In draft-gear, a frame having a spring-receiving pocket, and means for varying both the length and width of the pocket.

5. In draft-gear, a frame having a spring-receiving pocket, and detachable blocks for 50 varying the width of the pocket.

6. In draft-gearing, a frame having a spring-receiving pocket, there being an opening formed in the wall of the pocket, and a detachable block adjustable to a position 55 within the pocket and having a lug extending through said opening.

7. In a draft-rigging, the combination with the sills and cheek-plates having follower-stops rigidly attached to said sills, of guides 60 for the follower vertically adjustably positioned in relation to said cheek-plates.

8. In a draft-rigging, the combination with the sills and cheek-plates having follower-stops rigidly secured thereto, of interchangeable guides for the follower for variably po-

sitioning the same in relation to said cheek-plates and sills.

9. In a draft-rigging, the combination with convertible side castings having integral front and rear stops and integral upper guides for the followers, of removable insert or conversion pieces, substantially as specified.

10. In a draft-rigging, convertible side castings having upper integral guides and lower removable guides and front and rear stops for the followers, and provided with removable insert or conversion pieces and abutting against said rear stops, substantially as specified.

11. In a draft-rigging, the combination with side castings having each front and rear stops and integral upper guides for the followers, of insert or conversion pieces abutting against said front and rear stops and furnished each with a stop, substantially as specified.

12. In draft-gear, a frame having spring-receiving pocket, and a reversible plate forming the bottom of said pocket.

13. In draft-gear, a frame having a spring-receiving pocket, and a reversible lug-strap forming the bottom of the pocket and adjustable to alter the effective height of said pocket.

14. In draft-gear, a frame, a reversible carry-iron for supporting the draw-bar at different heights, and means for rigidly locking said carry-iron in either of its positions.

15. In a draft-gear, the combination with the draw-bar, of a carry-iron supporting the draw-bar and having a vertical adjustment, and a draw-spring connection with the inner end of the draw-bar, said draw-spring connection having a corresponding vertical adjustment to that of the carry-iron.

16. In draft-gear, a frame having lugs for embracing the transom, and interchangeable and adjustable filling-blocks disposed between the sides of the transom and the lugs.

17. In draft-gear, a frame having spaced lugs for embracing the transom, and interchangeable blocks adjustable to varying positions with respect to the transom and the lugs.

18. In a draft-gear, the combination with the vertically-disposed web-plates arranged between the longitudinal sills and provided with edge flanges, of a transversely-disposed bracing-plate extending between the web-plates and resting on said flanges in a position to the rear of the end sill of the frame, and securing-bolts extending through said bracing-plate and end sill and serving to prevent rearward movement of all of the plates.

19. In a draft-gear, a pair of plates having spring-receiving pockets and arranged to extend partly under the center sills of the car, the tops of the plates having projections arranged to enter bottom recesses in said sills and the rear portions of said plates having recesses to receive the body-transom, the

plates having vertically-disposed webs arranged to fit snugly against the inner vertical faces of the sills and provided with bosses entering openings formed in said vertical faces, and horizontal securing-bolts extending through the webs, the bosses and the sills and forming the sole supports of said plates.

In testimony that I claim the foregoing as my own I have hereto affixed my signature in the presence of two witnesses.

JOHN LANGE, JR.
